UNITED STATES PATENT OFFICE.

ALPHONSE A. ROYEAU, OF LE MANS, FRANCE.

MACHINE FOR THE MANUFACTURE OF CANDLES.

SPECIFICATION forming part of Letters Patent No. 269,885, dated January 2, 1883.

Application filed August 24, 1882. (No model.) Patented in France August 4, 1880, No. 138,105; in Belgium October 22, 1880, No. 52,833; in Italy October 30, 1880, XXIV, 389; in Germany November 2, 1880, No. 14,452; in England November 12, 1880, No. 4,666; in Spain November 15, 1880, No. 591 and No. 1,252, and in Austria-Hungary December 25, 1880, No. 34,974 and No. 40,388.

To all whom it may concern:

Be it known that I, ALPHONSE ALEXANDRE ROYEAU, a citizen of the Republic of France, residing at Le Mans, (Sarthe,) France, have invented a new and useful Machine for the Manufacture of Candles, (for which I have obtained Letters Patent in France August 4, 1880, No. 138,105, for fifteen years; Belgium, October 22, 1880, No. 52,833, for fifteen years; England, November 12, 1880, No. 4,666, for fourteen years; Germany, November 2, 1880, No. 14,452, for fifteen years; Austria-Hungary, December 25, 1880, No. 34,974 and No. 40,388, for fifteen years; Spain, November 15, 1880, No. 591 and No. 1,252, for twenty years; Italy, October 30, 1880, No. 389, Volume XXIV, for fifteen years;) and I do hereby declare that the following is a full, clear, and exact description of the invention, which will enable others skilled in the art to which it appertains to make and use the same, reference being had to the accompanying drawings, and to the letters or figures of reference marked thereon, which form a part of this specification.

The improvements I am about to describe by the aid of the accompanying drawings totally modify candle-making machines, as regards economy of construction and labor, the results obtained, and the quality of the products.

In principle my new machine is double. It comprises two series of rows of independent molds arranged in one frame, which molds are easily cleared one after the other, so that one casting having just been made in the front series, for example, the work-woman without loss of time proceeds to the removal of the back series and to the subsequent work for the casting.

If, as shown in the annexed drawings, the machine is arranged for the manufacture of candles every eight or ten minutes, exactly the time for the removal and casting, the work-woman passes from one series to the other, molding and removing without interruption; and if rows of eight molds and thirty-two rows per series are employed, the enormous production in round figures of fifteen thousand candles in ten hours' work may be reached, all ready to be delivered for use; and as there is no limit to the number of rows of molds, that number may extend very much beyond what is shown

in the drawings, and consequently the production can be even doubled or trebled.

The molds, arranged in special cases or jacks, are cooled after casting by the admission of cold water directed from below, which strikes the coldest part of the candle—namely, the head—first, then gradually rises until it completely fills the whole space surrounding the molds. Then, the admission of water continuing, a current is established from the cold-water inlet to the outlet. This current is stopped when it is proved that the water on leaving the machine has the same temperature as on entering. The candles may then be left at rest, or immediately the cold water has been drawn off the hot water necessary for freeing the candles from the molds may be admitted. This admission of hot water is effected in a direction opposite to that of the cold water, no longer at the head of the candle, but at the bottom, and instantly to all the molds, by a new arrangement of mechanism. The effects of dilatation are afterward general, and allow of effecting the removal of the candles without effort and without accident. The products obtained are of great beauty, very compact, and if they are tallow candles they possess the varnish and brilliancy of stearine products.

I have said that the two series of molds (which each form what I call a "case") are independent one of the other. They have each their mechanism for lifting and for the admission of hot and cold water, but they are specially remarkable in that they are dependent upon the common frame for their necessary support only, and that they can be placed in and taken out of this frame with the greatest facility, whether for the purpose of substituting one case for another in order to make a different number of candle or for the purposes of inspection or repair of some of the parts. I may mention, farther, that the air drawn and forced in by the admission of water meets with no obstacle, as there is a judicious arrangement of air-vents, and consequently neither hot nor cold water is in any case stopped in its action.

In the drawings, Figure 1 is an elevation of one face of the machine. Fig. 2 is an end view, and Fig. 3 a transverse section. Figs. 4

and 5 show an elevation and a plan of a row of molds. Fig. 6 shows, partly in vertical section and partly in front view, some of these rows of molds. Figs. 7 and 8 are details of the wick-pinchers. Fig. 9 shows the adaptation of one of the ends of a case to one of the side frames. Figs. 10 and 11 show one of the bearings for the shafts arranged to allow the putting in place and removal of these shafts without dismounting the frame. Finally, Fig. 12 shows in elevation a new can for effecting at one operation the casting of the tallow or other material into each of the molds, forming together one row.

15 The frame of the machine is of a form and dimensions designed to support two cases. It is composed of two side frames, *a a*, united firmly together by four stretchers, *b*. At the upper part and inside the side frames, *a a*, are 20 furnished with ribs *a' a'*, Fig. 9, which form two slides or guides, in which are fitted the ends of the metallic cross pieces or plates, *c c*, which carry and inclose the rows of molds. Each case thus comprises two cross-pieces, *c c*, and a certain number of rows of molds, forming together a whole, which can be put in and taken out of the side frames, *a a*, at pleasure, the ribs *a' a'*, which exist in front and behind the frame, extending for that purpose as far 25 as the front and back edges.

In the drawings, Figs. 4, 5, and 6, a row of molds for each case contains eight molds, each formed of a copper casing or jacket, *d*, and of the "tin-mold," properly so-called, *f*, centered 30 in the said casing. The latter is closed at the bottom, and is soldered at the top to a shelf, *e*, common to the eight molds, and fixed by four screws to a wooden or metal cross-piece, *g'*, which rises above the sides of the case *c*. The 35 mold *f* is held in place by tightening the nut *f'* on the bottom of the jacket. Two india-rubber washers, *d'* and *d''*, secure the tightness of the joints above and below. The eight jackets *d* communicate near the bottom by eight 40 branches with a pipe, *g*, which connects with the principal conduit *G*. Near the top they are also connected by eight branches formed in the shelf *e* with a pipe, *h*, connected at one end with a pan or trough, *H*, and receiving at 45 the open end an easy-fitting pipe, *h'*, pierced with eight holes corresponding to the branches. The pipe *h'* is closed at its outer end, and it is there fixed to a piece, *i*, the object of which is to communicate to it the turning movement required for opening and closing the branches. 50 Level with these latter, each jacket has an india-rubber washer, *d''*, which leaves a small annular hollow round the mold, the object of which is to form an obstacle to the outlet 55 above of the hot water admitted and to retard the ascension of the cold water. The intervals between two consecutive shelves *e* are covered by cover-joints *e'*, the convexity of which returns the tallow into the bottom of 60 the said shelves. All the pieces *i*, which act as cranks, are connected to a single bar, *j*,

which is drawn out or pushed in at pleasure by a lever, *j'*, and a connecting-rod, *j''*, according as it is desired to open or close, by a single motion all the pipes *h*. The bar *j* goes through 70 openings formed in the sides *a* of the frame. A small wooden or metal board, *v*, covers this part of the mechanism and carries the trough *v'*, into which escape any excess of material and the waste. It is only necessary to unbolt 75 the small board *v* in order to take out the case *c*.

The pan or trough *H* is for the admission of hot water and also for the outlet of cold water. It is for that purpose furnished at one end 80 with the emptying pipe and cock *h''*. The conduit *G* is for the admission of cold water. It carries at its two ends, and even from place to place, if necessary, air-pipes *g' g''*. *g''* is the admission-cock; *g''*, the emptying-cock. Each 85 case has its own conduits and admissions of hot and cold water.

The lower cross-pieces, *b*, of the frame support the box *K*, which contains the balls of wick, and which for that purpose is provided 90 with the necessary arrangements for securing a regular unwinding of the wicks and facility of putting in place. The wicks *m*, after having passed through the top of the box *K*, enter the molds, being subjected to a suitable 95 tension, and are then fixed securely to the wick-pinchers. These pinchers, which are distinct for each row of molds, are pieces of brass or other metal, *p*, bolted or riveted to two angle-irons, *q q*, which extend from end to end of the 100 machine. These pieces are shaped in such manner that rings *p'*, equal in number to the molds of each row, can be fixed at equal distances on the said piece *p*, Figs. 7 and 8. In these rings is fitted an iron rod, *p''*, having 105 notches *p'''* cut therein opposite each of these rings. A screw, *p''*, prevents the rod *p''* from turning on itself during the longitudinal movements which are communicated to it by the tightening of the nut *p''*, bearing against the 110 fixed abutment *p''*, or by hand, or otherwise, in the contrary direction. The wicks *m* are placed in the notches *p'''*, when the latter are drawn out of the rings *p'*, the nut *p''* is then turned, and all the notches enter with the wicks into 115 the rings *p'*, by which the said wicks are firmly pinched and held. In order to disengage the wicks, the nut *p''* is unscrewed and the rod *p''* is pushed back by hand or by a light blow of a hammer. The angle-irons *q q* are carried by 120 two cast-iron cross-heads, *n n*, which slide on the two vertical guides *o o*, and are raised and lowered in the following manner: Each of the cross-heads *n* is attached to two racks, *r r*, which gear with two spur-pinions, *r' r'*, keyed 125 on the same horizontal shaft *r''*. The shaft, *r''* turns in bearings *s' s'*, bolted to the frame, and receives, near the middle of the machine, a bevel-pinion, *s*, gearing with a similar pinion, *t*, keyed on the end of the shaft *t'*, which extends from one side frame to the other, resting in the bearings *t''*, Figs. 10 and 11, adapted 130

to the frame. At one of its ends the shaft t' is furnished with a crank-handle, t^3 , which, as will be understood, effects simultaneously and regularly the raising or lowering of the two cross-heads n appropriate to each case, c . Ratchet-wheels x , with retaining-pawl x' , are arranged either on one of the shafts, r^2 , or on one of the ends of the principal shaft, t' .

The machine has two crank-handles—one for the use of each case and one at each end—in order to leave the movements entirely independent. It is the same with the two levers j' which command the opening and closing of the pipes g .

15 Action of the machine: In order to put the machine to work, the work-woman attaches the wicks of one case to the pinchers, the latter being a little above the shelves, and she then brings the can (shown in Fig. 12) full of hot 20 tallow, and passing it between each of the rows of molds, she fills them one after the other from the first to the last. Waiting a few minutes after filling, she admits the cold water, producing a current from below upward until she 25 observes that the water enters and leaves at the same temperature. In order to establish this current, she opens the cocks g^2 and h^2 , and also the pipes h , of each row. The cocks g^2 and h^2 are then closed. g^3 is opened to empty 30 out the cold water. It is afterward closed, as well as the pipes h , ready for the admission of hot water into the pan or trough H . This hot water is afterward directed into the molds by moving the lever j' , and it is emptied out after 35 having moved the lever j' in the reverse direction and opened the cocks g^3 . Before the admission of the hot water, which immediately precedes the removal of the candles, the work-woman has placed herself opposite the second 40 case, where she has recommenced the same operations. Then, when the operations of attaching the wicks and the casting are completed, she returns to the first case to admit the hot water and to effect the removal of the 45 candles from this first case, after which she recommences a fresh casting before returning to the other side of the machine.

The can, Fig. 12, is of a capacity suitable for filling the whole of a case. It carries a pouring-pipe closed at its outer end and perforated with eight holes placed at the same distance apart as the molds. Another pipe, y , is fitted easily over the first named. It is furnished with the handle y' , and also with eight openings, which are brought at the proper time 55 so as to uncover the holes or jets of the inner pipe.

When these machines are of large size I propose to connect the pouring-cans to carriages which circulate between and over two machines and which will carry the material to be cast, such as tallow, stearine, or other. The cans will thus be easily handled, as they will only require to contain the material for filling one case, and it will suffice to connect them in 65 a supple and flexible manner to the carriages.

The improvements above described are partly applicable to existing machines.

I claim—

1. The combination of the frame a , having 70 ribs $a' a'$, with the cross pieces or plates $c c$, and rows of molds $d d$, substantially as herein shown and described.
2. The molds d , having branches $g h$, combined with inner molds, f , nut f' , and washers $d' d^2$, substantially as herein shown and described. 75
3. The tallow-molds f , combined with outer mold, d , branches $g h$, vessels $G H$, and cocks g^2, g^3 , and h^2 . 80
4. The perforated pipe h' , combined with branched pipe h , and with rods i , bar j , and lever j' , for operation substantially as herein shown and described.
5. The tallow-can having discharge-pipe 85 with perforated side and combined with outer perforated pipe, y , having handle y' , substantially as herein shown and described.

ALPHONSE ALEXANDRE ROYEAU.
